UNITED STATES PATENT OFFICE.

FRANK W. ROBINSON, OF READING, PENNSYLVANIA, ASSIGNOR TO THE NOLDE & HORST CO., OF READING, PENNSYLVANIA, A CORPORATION OF PENNSYLVANIA.

CLOCKING ATTACHMENT FOR CIRCULAR-KNITTING MACHINES.

1,203,131.

Specification of Letters Patent. Patented Oct. 31, 1916.

Application filed October 14, 1914. Serial No. 866,579.

To all whom it may concern:

Be it known that I, FRANK W. ROBINSON, a citizen of the United States, residing at Reading, in the county of Berks and State 5 of Pennsylvania, have invented certain new and useful Improvements in Clocking Attachments for Circular-Knitting Machines, of which the following is a specification.

My invention relates to an improved attachment for circular knitting machines whereby an additional thread or threads may be interwoven with the fabric when required, so as to produce either plain-stripe or various so-called clock-work effects as 15 desired.

The invention is fully described in connection with the accompanying drawing and the novel features are specially pointed out in the claims.

20 Figure 1—is an elevation, partly in section, showing my improved mechanism in preferred form, as applied to a machine. Fig. 2—is a partial view at right angles to Fig. 1 showing in a somewhat larger scale the thread-carrier suspension device and the co-operating finger-guide carrier head. Fig. 3—is a plan view of the thread carrier suspension device. Fig. 4—is a plan view of the finger-guide carrier head.

30 The needle cylinder 2, needles 3, cam cylinder 4, and frame 5, are parts of an ordinary circular knitting machine in which the cam cylinder is rotated from a drive shaft 6.

A column-bracket 7—8, fixed to the frame 35 5, directly supports a thread-carrier suspension device 10; by means of a stem portion 11 vertically slidable in the axially ap- 40 ertured end 9 of said bracket, and a fixed collar 12 and set screw 13, as indicated.

45 The additional thread or threads, 15, 15^a, which are to be interwoven with the circularly knitted fabric of the machine, each extends from an additional bobbin 16 mounted on an arm 17 at the upper end of 50 45 the stem 11, to the depending end 20 of a suspended thread-carrier finger 21 with which it is swung around so as to engage determined needles, as hereinafter described. The carrier finger 21 is suspended, 55 as shown, by means of a universal-joint connected to the suspension device 10; the latter having a socket-bearing 22 in which a ball-enlargement at the upper end of the finger is loosely mounted substantially as 60 55 set forth in Patent No. 1,077,304 issued to

me November 4, 1913. My present invention consists in providing means for imparting, when desired, a needle-engaging swing to the free end of a thread-carrying finger or fingers so suspended, and for automatically varying such swing so as to cause engagement with any desired number of needles in the knitting of each course and thereby enable the satisfactory production of any predetermined design of striping or clocking; as fully set forth by reference to the specific construction illustrated in the drawings. This construction shows a pair of thread-carrying fingers 21 for producing opposite stripes or clocking; each 60 65 being provided with a suspension point engaged in a socket bearing 22 of the suspension device 10. For imparting swinging movement to the fingers, each is provided, as shown, with a rigid laterally extending 70 75 operating arm 25 having a rigid head plate 26 with a central cam-contacting roller or projection 27; and with additional cam-contacting rollers 28 and 29 located on opposite sides of said central roller 27, upon 80 85 centrally pivoted carrier arms which have stops to positively limit their pivotal swing. These pivoted roller-carrying arms 38 are connected by springs 32, 32 to other rigid operating arms 37, 37 of the finger 85 90 95 100 105 110 21, arranged at right angles to the arm 25, and both fingers are pressed radially inward by a connecting spring 31; so that contact of a suitable cam 30 carried by the rotary cam cylinder 4, with the series of rollers 28, 27, 29 arranged in its path, will impart a controllable needle-engaging swing to the free end of the finger. The movements of the finger along the needles are effected through the spring-connected pivoted roller arms, while the radial movements to engage the threads are effected through the central roller 27. The control of this movement of the thread-car- 100 105 110 115 120 125 130 135 140 145 150 155 160 165 170 175 180 185 190 195 198 200 205 210 215 220 225 230 235 240 245 250 255 260 265 270 275 280 an intermediate guide-collar 40, which is engaged in a guide-way of the adjustably fixed head 35; this guide way being formed by parallel walls 41, 41 adapted to control 5 both the radial and lateral movements of the swinging finger. To provide for varying the extent of the lateral movements, as determined by the different number of needles which the additional thread may be 10 desired to engage for determined swings of the cam cylinder, these guide walls 41, 41 are provided with opposing vertical series of separately adjustable stops 42, 42. These stops operate in pairs, proper vertical adjustment of the head 35 serving to bring 15 the collar 40 into guiding contact with one or another of the differently spread pair of stops, during different swings of the finger. In order that desired ornamental effects 20 may be reliably and accurately produced it is practically necessary that the adjusting movements of the finger-guide carrier head 35 be automatically produced, and that the cam 30 be correspondingly moved into operative or inoperative position. Pattern-controlled means for jointly effecting these 25 movements are therefore provided; comprising, as shown, a lifting-rod 50 for the finger-guide carrier head 35, which rod is arranged to be 30 to be operated by lugs 51, 51^a of varying heights on a pattern chain 52; and a raising and lowering rod 53 for said cam 30, which rod is operated by a pin 54 when the latter is moved into operation by other pattern-chain lugs 55 adapted to so move said pin 35 through the medium of a suitable lever 56-57. As indicated the pattern chain 52, which is operated from the shaft 6 by means of a pawl device 60-61, is arranged to be 40 automatically thrown into operation when needed, by an independently driven pattern chain 62 which controls said pawl 60, but this specific arrangement of the pattern mechanism is of course immaterial, so long 45 as the operation of the head 35 and cam 30 are harmoniously effected thereby as described. The required automatic movements of the cam-rod 53 are produced, as shown, by control of a star-wheel 65, suitably mounted in the cam cylinder 4 with the pattern-projected pin 54 in its path; the handled device 66 indicated being merely provided to permit of throwing the cam 30 entirely out of action when desired. 50 It will be understood from the foregoing 55 description that when the cam 30 is set in operative position it imparts a needle-engaging swing to the finger or fingers 21 at each rotation of the cam cylinder; and that 60 the extent of this swing is varied, as determined by the number of needles on which it is desired to engage the additional thread at different rotations in order to produce desired ornamental effects,—first, by corresponding adjustment of the stops 42-42

carried by the head 35, and second by corresponding adjustment of the head itself; and furthermore that the required movements of the head 35 and cam 30 are in each case automatically effected so as to positively 70 produce determined designs cheaply and satisfactorily.

The specific construction illustrated and described may obviously be modified without departing from the invention as defined 75 in the claims.

What I claim is:

1. A clocking attachment for circular knitting machines comprising a thread-carrier finger having a universal-joint suspension 80 point, means for imparting an intermittent needle-engaging swing to the free end of said finger, and means for varying said swing as determined by the number of needles to be engaged. 85

2. A clocking attachment for circular knitting machines comprising a thread-carrier finger having a universal-joint suspension point, means for imparting an intermittent needle-engaging swing to the free end of 90 said finger, and pattern-controlled means for varying said swing as determined by the number of needles to be engaged. 95

3. A clocking attachment for circular knitting machines comprising a thread-carrier finger having a universal-joint suspension point, means for imparting an intermittent needle-engaging swing thereto, a finger-guide having a plurality of pairs of oppositely arranged finger stops, and means for 100 making operative one or another of said pairs of stops. 105

4. A clocking attachment for circular knitting machines comprising a freely-suspended thread-carrier finger, means for imparting an intermittent needle-engaging swing thereto, a finger-guide having a plurality of pairs of separately adjustable oppositely arranged finger stops, and means for making operative one or another of said 110 pairs of stops. 115

5. A clocking attachment for circular knitting machines comprising a thread-carrier finger having a universal-joint suspension point, means for imparting an intermittent 115 needle-engaging swing to the free end of said finger, a finger-guide having a plurality of pairs of oppositely arranged finger stops, and pattern-controlled means for making operative one or another of said pairs of 120 stops. 125

6. A clocking attachment for circular knitting machines comprising a fixed bracket, a finger-suspending device supported thereby, a thread-carrier finger freely suspended from said device, an adjustably-supported finger-guide having a plurality of pairs of oppositely arranged finger stops, means for imparting an intermittent needle-engaging swing to said thread-carrier finger, and pat- 130

tern-controlled adjusting means for said guide.

7. A clocking attachment for circular knitting machines comprising a thread-carrier finger having a universal-joint suspension point, means for normally imparting a maximum intermittent needle-engaging swing to the free end of said finger, and means for variably limiting said swing as determined by the number of needles to be engaged.

8. A clocking attachment for circular knitting machines comprising a thread-carrier finger having a universal-joint suspension point, means for normally imparting a maximum intermittent needle-engaging swing to the free end of said finger comprising controlling spring connections to the latter, and means for variably limiting said swing as determined by the number of needles to be engaged.

9. A clocking attachment for circular knitting machines comprising a thread-carrier finger having a universal-joint suspension point, means for normally imparting a maxi-

mum intermittent needle-engaging swing to 25 the free end of said finger, means for variably limiting said swing as determined by the number of needles to be engaged, and a pattern mechanism arranged to automatically control both said swinging and limiting means.

10. In a clocking attachment for circular knitting machines, a thread-carrier-finger having a universal joint suspension point provided with a horizontal operating arm 35 having a rigid head plate and a central cam-contacting projection, side cam-contacting projections each having a limited pivotal movement on said head plate, and other rigid operating arms having spring connections to said pivotally movable side projections.

In testimony whereof I affix my signature in presence of two witnesses.

FRANK W. ROBINSON.
